UNITED STATES PATENT OFFICE.

HARRY H. LABADIE, BURTON B. BEERS, AND THEODORE A. KRUEGER, OF CHICAGO, ILLINOIS; SAID BEERS AND SAID KRUEGER ASSIGNEES TO KNICKERBOCKER CASE COMPANY, OF CHICAGO, ILLINOIS, A CORPORATION OF ILLINOIS.

CABIN BAG.

Application filed September 11, 1922. Serial No. 587,572.

To all whom it may concern:

Be it known that we, HARRY H. LABADIE, BURTON B. BEERS, and THEODORE A. KRUEGER, citizens of the United States, residing at Chicago, in the county of Cook and State of Illinois, have invented certain new and useful Improvements in Cabin Bags, of which the following is a specification.

10 Our invention relates to cabin bags and it has for its principal object the provision of a new and improved form and arrangement of parts whereby a lighter bag may be produced without materially weakening the structure. In bags of this type heretofore in use, it has been customary to employ a metal frame work which, in the manufacture of the bag, has been completely covered with leather or other suitable material. In the form of bag ordinarily produced, heretofore, it has been necessary to do a very considerable amount of hand stitching, whereby it has been impossible to produce a bag of this type at as reasonable a cost as has been desired. Moreover, in the use of bags of that type, where they have been subjected to hard usage, there has been undue wear upon the end portions of the bag at the top, with the result that the metal parts have been very often stripped of the leather covering at this point long before the bag has shown any considerable wear at any other point. It is the object of our invention to so change the construction and reinforcement of the bag that no undue wear shall occur at any particular point, that the bag may be produced with a much smaller amount of hand work whereby the bag may be produced at a more reasonable cost, and so that the bag may still be of sufficient strength for carrying the heavy load of samples or other parts.

45 The preferred means by which we have accomplished our several objects are illustrated in the accompanying drawing and are hereinafter specifically described. That which we believe to be new and desire to cover by this application is set forth in the claims.

50 In the drawing:

Fig. 1 is a perspective view of a bag embodying our improved construction.

Fig. 2 is a similar view but with one of

the top flaps turned upwardly and outwardly.

55

Fig. 3 is a cross-section through the bag.

Fig. 4 is an enlarged detail view, being substantially a section taken on line 4-4 of Fig. 3.

Fig. 5 is an enlarged detail view, being substantially a section on line 5-5 of Fig. 4.

Referring to the several figures of the drawings, 10 indicates the ends of the body of the bag, and 11 indicates the sides of the body, being formed of any suitable material so as to give the requisite strength and stiffness. 12 and 13 indicate closing flaps which are hingedly secured along their side edges to the upper edges of the sides 11 of the body. As is best shown in Fig. 3, 70 the flap 13 overlaps the flap 12 when the two flaps are turned downwardly into their body closing position above the ends 10 of the body.

As is best shown in Fig. 5, the free edge 75 of the flap 13 is provided with a metal reinforcing member 14 in the form of a bar, having turned down ends 15, as is clearly shown in Fig. 2. The turned ends 15 are so disposed that they are adapted to embrace the free edges of the flap 12 when the flaps are turned down into their body closing position. The two flaps 12 and 13 are provided with latching devices 16 of any approved type, and a handle 17 is provided upon the flap 13 for carrying the bag.

For providing the required stiffness for the flaps 13 and 12, so as to enable the bag to be carried properly through the use of the handle 17, we have provided angle bars 90 18 on the inner faces of the flaps, such angle bars extending from end to end of the flaps so as to engage at their ends with the inner faces of the ends 10 of the body. These angle bars, therefore, serve not only to 95 strengthen the flaps longitudinally but serve also to prevent endwise movement of the flaps with respect to the body by their engagement with the ends 10. As will be appreciated from an inspection of Fig. 5, the 100 operation of applying the strengthening bars 18 is very simple. The covering sheet 19 of leather or other suitable material is first folded about the flange of the bar and a plurality of rivets 20 are inserted through 105 the flange and through the two thicknesses

of the leather. The leather is then folded and glued in position about the other flange of the bar, whereby a very neat appearance is obtained without the necessity for stitching or other expensive hand operations.

In the construction shown, the flap 12 is also provided with a reinforcing bar 21 at its free edge portion, such bar 21 being adapted to rest immediately beneath the bar 10 14 of the flap 13.

For further reinforcing the structure, we have provided latch devices 22 hingedly mounted upon the ends 10 of the body, in position to engage pins or lugs 23 carried by the turned ends 15 of the bar 14. As will be readily understood, with the hinged latch devices 22 in engagement with the lugs 23, the flap 13 is held against upward movement, serving in turn to hold the flap 20 12 also in its body closing position. By the use of the latch devices 22 in connection with the latch devices 16 and the bars 18 which protect against longitudinal movement of the flaps with respect to the ends 25 10 of the body, we have provided a construction which is very rigid and strong and which at the same time is very simple and can be produced at a very moderate cost as compared with the old construction in 30 35 which a metal frame work was employed for mounting the flap upon the upper end of the body.

While we prefer to employ the construction illustrated by the drawing, it will be understood that we do not desire to be limited to the use of the precise details as shown except as the same are hereinafter specifically claimed, inasmuch as it is evident that various changes might be made 40 in the construction without departing from the spirit of the invention.

We claim:

1. A cabin bag comprising a non-metallic body portion having oppositely disposed 45 ends and sides, and flaps of the same material hingedly secured along the sides of the body and adapted to fold downwardly over the ends of the body with one flap overlapping the other, a reinforcing metal bar secured along the free edge of the overlapping flap and having downturned edges adapted to enclose the free edges of the other

flap, and latching means carried by the flaps for securing the flaps together.

2. A cabin bag comprising a non-metallic 55 body comprising oppositely disposed ends and sides, and flaps of the same material hingedly secured along the sides of the body, and adapted to fold downwardly over the ends of the body with one flap overlapping 60 the other, a metal bar extending along the free edge of the overlapping flap and having turned ends adapted to embrace the other flap, said metal bar having connection with the overlapping flap only along the free edge 65 thereof, and latching means carried by the ends of the body adapted by engagement with the turned ends of the metal bar to hold the overlapping flap in its body closing position. 70

3. A cabin bag comprising a body having oppositely disposed ends and sides, flaps hingedly secured along the sides of the body and adapted to fold downwardly over the ends of the body with one flap overlapping 75 the other, angle bars secured on the inner faces of said flaps near their free edges, and latching means for securing said flaps together in their body closing position.

4. A cabin bag comprising a body having 80 oppositely disposed ends and sides, flaps hingedly secured along the sides of the body and adapted to fold downwardly over the ends of the body with one flap overlapping 85 the other, metal reinforcing bars secured on the inner faces of the flaps in position to engage the ends of the body when folded down in body closing position, and latching means for securing said flaps together in 90 their body closing position.

5. A cabin bag comprising a body having oppositely disposed ends and sides, flaps hingedly secured along the sides of the body and adapted to fold downwardly over the ends of the body with one side overlapping 95 the other, metal reinforcing bars secured on the inner faces of the flaps in position to engage the ends of the body when folded down in body closing position, and latching means for securing said overlapping flaps 100 releasably to the ends of the body.

HARRY H. LABADIE.

BURTON B. BEERS.

THEODORE A. KRUEGER.
